UNITED STATES PATENT OFFICE.

WILLIAM A. FLANNERY, OF MILFORD, MASSACHUSETTS.

CIGARETTE-ROLLER.

1,115,918.

Specification of Letters Patent.

Patented Nov. 3, 1914.

Application filed March 20, 1914. Serial No. 826,110.

To all whom it may concern:

Be it known that I, WILLIAM A. FLANNERY, a citizen of the United States, residing at Milford, county of Worcester, State of Massachusetts, have invented an Improvement in Cigarette-Rollers, of which the following description, in connection with the accompanying drawing, is a specification, like characters on the drawing representing like parts.

10 This invention has for its object to provide a novel device by which a cigarette can be easily and accurately rolled.

15 Many persons experience more or less difficulty in gracefully rolling a cigarette and by this invention I aim to provide a cigarette roller by means of which a person can readily roll a cigarette and do it in such a way that the fact that he is using a cigarette 20 roller for this purpose will not be apparent.

In order to give a proper understanding 25 of my invention I will describe a selected embodiment thereof which is illustrated in the drawings and then point out the novel features thereof in the appended claims.

Referring to the drawings, Figure 1 is a perspective view of a cigarette roller; Fig. 30 2 is a perspective view showing the cigarette roller having a cigarette wrapper in position with the tobacco placed thereon; Fig. 3 shows the cigarette formed in the cigarette roller; Fig. 4 shows the rolled cigarette being withdrawn from the roller; Fig. 5 shows the preferred way of holding the cigarette 35 roller when the tobacco is being applied thereto.

My improved cigarette roller comprises a body portion 1 which may be made of celluloid, paper or any other material which is 40 flexible and resilient. The body portion 1 is normally flat that is when unrestrained, it will assume the flat shape shown in Fig. 1. The body portion has at each edge thereof lips 2 adapted to embrace the edges of a cigarette wrapper 3 and hold it in position.

45 My improved cigarette roller will preferably be made of less length than the cigarette wrapper 3 so that when the wrapper 3 is slipped under the lips 2, one end of the cigarette wrapper will project beyond the end of the holder, as shown in Fig. 2. My cigarette roller is also preferably provided with guiding marks 4 thereon which extend longitudinally thereof, the purpose of 55 these marks being to form a guide for the deposit of tobacco on the cigarette wrapper.

In using the device a cigarette wrapper is slipped under the lips 2, as shown in Fig. 2, and because of the transparent quality of the wrapper the guiding lines 4 will be visible therethrough. The tobacco 5 is then poured onto the cigarette wrapper between the guiding lines 4, these lines constituting the means to indicate the proper position for the tobacco in order to secure a properly- 60 rolled cigarette. After the tobacco has been deposited on the cigarette wrapper, as shown in Fig. 2, then the wrapper and the cigarette roller can be rolled up into the shape shown in Fig. 3 and because of the resilient quality 65 of the roller it is comparatively easy to roll up the cigarette roller 1 with its contained wrapper into the form shown in Fig. 3. When this has been accomplished the end 6 of the rolled cigarette will extend beyond 70 the end of the cigarette roller 1, as shown in Fig. 3. The person then grasps the projecting end of the cigarette and withdraws 75 it from the end of the cigarette roller 1, while retaining the latter in its rolled position, as shown in Fig. 4. In rolling the cigarette the edge 7 of the cigarette wrapper 80 will be brought into position to overlie the edge 8 thereof as necessary in making cigarettes, and when the cigarette is withdrawn from the cigarette roller 1, as shown in Fig. 4, the cigarette is complete and the edge 7 is in position to be moistened 85 preparatory to sticking it onto the body of the wrapper. The cigarette can be thus easily 90 and perfectly made even by amateurs.

It is my intention to make the cigarette 95 roller 1 of a color similar to that of the cigarette wrappers so that it can be used without being observed. Moreover, by making the cigarette roller with the construction shown in Fig. 1, it can be used as a card case, for an ordinary calling card can be readily slipped in between the lips 2 which will 100 serve to stiffen the roller and hold it in shape when it is not in use, as well as to identify it.

One of the principal advantages of my invention results from the use of the two retaining lips 2 at opposite sides of the body 105 portion 1. By reason of the fact that two retaining lips are employed the cigarette wrapper will be firmly held at both edges and cannot, therefore, become displaced while the cigarette is being made. This being so it is possible for the person using my device to roll the cigarette with substantially 110

the same motions as he would if the cigarette roller were not used, but the use of the cigarette roller enables him to quickly and accurately form his cigarette much easier than could be done without the roller. The holding of the cigarette wrapper on both edges by the lips 2 is an important feature of the invention.

In filling the cigarette it is preferable to bend the cigarette roller up into a semi-circular shape, as shown in Fig. 5, thus making a trough to receive the tobacco 5. When the cigarette roller is bent into this shape the guiding lines 4 appear at the sides of the trough-shaped wrapper and give an indication as to how full to fill the wrapper. Moreover, the two lips 2, operate to compel the cigarette wrapper to assume the trough shape when the body portion is bent into the position shown in Fig. 5, for they hold the edges 7, 8 of the cigarette wrapper in proper position and prevent said edges from slipping relative to the body portion.

Having described my invention, what I claim as new and desire to secure by Letters Patent is:—

1. A cigarette-roller presenting a body portion of resilient flexible material which normally assumes a flat shape and is formed on each longitudinal edge with an in-turned cigarette - wrapper - retaining lip whereby when a cigarette wrapper is confined beneath said lips and the body portion is bent into a trough shape the wrapper will be held in proper position and caused to also assume a trough shape. 30 35

2. A cigarette roller comprising a body portion of flexible resilient material having on each longitudinal edge an inturned cigarette - wrapper - retaining lip and provided with two separated guiding lines extending longitudinally thereof by which the proper position for the tobacco on the containing cigarette wrapper is determined. 40

In testimony whereof, I have signed my name to this specification, in the presence of two subscribing witnesses.

WILLIAM A. FLANNERY.
